UNITED STATES PATENT OFFICE.

OLIVER W. BARTLOW AND RANSOM AULT, OF OMEGA, INDIANA, ASSIGNEES
TO SAID BARTLOW.

TIRE-COOLING TRESTLE.

SPECIFICATION forming part of Letters Patent No. 241,778, dated May 24, 1881.

Application filed October 11, 1880. (Model.)

To all whom it may concern:

Be it known that we, OLIVER W. BARTLOW and RANSOM AULT, of Omega, in the county of Hamilton and State of Indiana, have invented certain new and useful Improvements in Tire-Cooling Trestles; and we do hereby declare that the following is a full, clear, and exact description of the invention, which will enable others skilled in the art to which it applies to make and use the same, reference being had to the accompanying drawings, which form a part of this specification.

Fig. 1 is a view, in perspective, of a tire-cooling trestle embodying our improvements. Fig. 2 is a side elevation of the machine, the frame being tilted and the rim of the wheel projected into the water-trough. Fig. 3 is a rear elevation of the machine shown in the position last above-described, and Fig. 4 is a sectional detail view.

This invention has relation to tire-cooling trestles; and it consists in the improved features of construction and combination herein-after fully described, and particularly pointed out in the claims.

Referring by letter to the accompanying drawings, A designates a longitudinal frame composed of the horizontal pieces B B and the transverse pieces C C' C'', placed thereon and secured together by bolts D, passed down through metal strips E E, resting on the cross-pieces C C' C'', and fastened to place by screw-bolts D and nuts F.

G designates a transverse frame composed of the longitudinal pieces H, and the transverse pieces H' bolted to the under sides of the pieces H. Lateral movement of frame G is prevented by bars Z bolted to the under side of the bars H, and between the bars B B of frame A, as shown in Fig. 3, the pieces H H coming between the pieces B B and the metal strips E E of the frame A.

The frame A is pivoted between the upper ends of the legs J, the feet of which are let into a sill or cross-piece, K, to give them stability. The rear end of the frame A is provided with a hinged lever, L, which also serves as a leg for that end of the frame A.

The frame G is provided at its middle with the metal arch M, from which a spindle, N,

rises. From the lower side of the arch M an eye, P, projects, and a rod, Q, connects this eye P and the lever L. From the rear or upper piece, H, of the frame G a spring, R, having a handle, S, extends rearward and engages, 55 when the machine is operated, with catches T T' projecting from the inner face of one of the pieces B of the frame A. The frame G is intended to slide in the ways formed by the strips E E and pieces B B of the frame A. 60

U represents the water-trough, which is to be set in the ground, its mouth being even with the surface of the same. The trestle is to be set near the trough, so that when the frame A is tilted the frame G may slide down in the 65 ways in the same and carry the rim of the wheel into the trough.

The operation of the device is very simple and is as follows: The wheel is placed upon the spindle, the dish side of the wheel being 70 down. By then grasping the hinged lever L and elevating the rear end of the frame A the front part of the frame A will approach the water-trough, and while this is being done the spring R should be disengaged from the upper catch, T', and the lever L depressed to cause the frame G which carries the wheel to descend in the ways in the frame A and permit the rim of the wheel to enter the water, there to be revolved to extinguish the burning felly and 75 cool the tire. The plates V V on the frame G, and the strips E E on the frame A prevent the heated tire from burning the frames A or G. 80

By this device a set of tire can be put on in about one-third of the time required to put 85 them on in the ordinary way.

The device is simple and inexpensive, and its usefulness over the ordinary method of cooling tire is so obvious as to need no comment.

Having thus fully described our invention, what we claim as new, and desire to secure by Letters Patent of the United States, is—

1. In a tire-cooling trestle, the combination of the tilting frame A, and the sliding frame G mounted thereon, and adapted to carry the wheel to be treated, with the lever L, hinged to the frame A, and the connecting-rod Q, arranged between the lever L and the sliding frame, as shown and described. 100

2. In a tire-cooling trestle, the frame A, pivoted between the legs J, and having the strips E, hinged lever L, and catches T T', in combination with the frame G, provided with arch M, carrying the spindle N, and eye P, the spring R, having handles S, and the rod Q, substantially as specified.

5 In testimony that we claim the foregoing as

our own we have hereto affixed our signatures in presence of two witnesses.

OLIVER W. BARTLOW.
RANSOM AULT.
